LIGHTING FIXTURE

Theophile A. Stiffel, Chicago, Ill.

Application August 22, 1956, Serial No. 42,700

Term of patent 14 years

(Cl. D48—19)

Figure 1 is a perspective view of a lighting fixture, showing my design.

Figure 2 is an enlarged perspective view of a portion thereof.

Figure 3 is a view taken on lines 3—3 of Figure 2.

I claim:

The ornamental design for a lighting fixture, as shown.
